Fig. 2

To all whom it may concern:

Be it known that I, Louise M. Bryan, a citizen of the United States, residing at Dallas, Dallas County, Texas, have invented a new, original, and ornamental Design for a Child's Play Tray or Similar Article, of which the following is a specification, reference being had to the accompanying drawing, forming a part thereof.

Figure 1 is a top plan view of a child's play tray or similar article, showing my new design.

Figure 2 is a perspective view of the tray in closed position, and

Figure 3 is a top perspective view of the tray in open position, a portion of the lid being omitted for convenience of illustration.

The pig face, box and framed numerals are surface markings only. Other ornamentations on the tray are three dimensional.

The dominant features of my new design are shown in solid lines in the drawing.

I claim:

The ornamental design for a child's play tray or similar article, substantially as shown and described.
